UNITED STATES PATENT OFFICE.

WILLIAM MILLER, OF CINCINNATI, OHIO.

WATER-BACK FOR STOVES.

SPECIFICATION forming part of Letters Patent No. 258,098, dated May 16, 1882.

Application filed February 21, 1882. (No model.)

To all whom it may concern:

Be it known that I, WILLIAM MILLER, a citizen of the United States, residing at Cincinnati, in the county of Hamilton and State of Ohio, have invented certain new and useful Improvements in Water-Backs for Ranges, Stoves, &c., of which the following is a specification.

The object of my invention is to construct water-backs for ranges, stoves, &c., in such a manner as to enable said backs to support the panels or "long centers" ordinarily applied to the top plates of such cooking or heating apparatus. This result is accomplished by providing the upper part of the water-back with a hollow lateral extension of any suitable size and shape, said extension being either cast with the back or securely fastened thereto, and arranged to sustain the panels or long centers, as hereinafter more fully described, and set forth in the claims.

In the annexed drawings, Figure 1 is a plan, showing my improvements applied to a ten-hole range, a portion of one of the panels of the latter being broken away. Fig. 2 is an enlarged horizontal section of the central portion of the range, taken directly above the lateral extensions of the water-back. Fig. 3 is a vertical section of the range, taken in the plane of said extensions. Fig. 4 is a perspective view of a portion of one of the water-backs and its extension. Fig. 5 is a longitudinal section through one of the backs and its attachments.

A represents the top plate of a range or stove or other cooking or heating apparatus, said plate being provided with customary detachable panels or long centers, B, fitted with lids or covers C. The fire-box D is lined on one side with a water-back, composed preferably of two horizontal shells, E E', located one above the other, and joined together by a short neck, F. Shell E is pierced at its rear end, as at e, for attachment of the inlet or cold-water pipe, while the other shell, E', is similarly perforated at e' to receive the outlet or hot-water pipe.

The upper member, E', of the back is provided with a hollow lateral extension, G, which extension may be integral with said back, as seen in Figs. 3 and 4; or it may be bolted thereon, as represented in Fig. 5; or said ex-

tension may be applied to the back in any manner that will afford a water-tight joint. The holes g, formed in the ends of this extension by the "core-prints," may be closed with screw-threaded plugs H; or said holes may have engaged with them pipes I, to assist in maintaining the circulation of water in the back E E' G.

The opposite side of fire box D is provided with a precisely similar arrangement of shells, I I', and lateral extension J. K K' are the outlet-pipes of these two opposite water-backs E E' G and I I' J.

Let the grate, and N N' portions of the ovens of the range.

When my improvements are applied to a range the upper surface of the two lateral extensions G J are practically in the same horizontal plane as the under side of the panels or long centers B. Consequently the center panels and the two contiguous panels are securely supported on said extensions, as seen in Figs. 1 and 3; but the panels at the extreme opposite ends of the range, not being subjected to a very intense heat, do not require the assistance of such extra supports. Evidently the panels thus supported will not warp nor sag down in the center, neither will they be liable to crack when very heavy utensils are set upon them. Furthermore, it is apparent that water circulates freely within the extensions G and J, thereby causing them to add to the heating capacity of the back, and enabling the range to furnish a greater quantity of hot water. I have described these extensions G J as applied to water-backs composed of two communicating shells, through which the circulation takes place in the direction indicated by the arrow in Fig. 5; but the invention is not to be limited to any special form of hot-water apparatus, as it is evident said extensions may be arranged for use with backs composed of pipe-coils or otherwise. In some cases these extensions need not come in direct contact with the under side of the panels; but the latter may have depending flanges or a series of lugs adapted to rest on top of said extensions; or detachable members may in some cases be interposed between said panels and supports G J. Finally, where a supply of water cannot be obtained, the shells or other linings of the furnace may be traversed with a current of air,

so as to highly heat the latter and discharge it through the openings *g* into the fire-box, and thereby promote combustion of the fuel.

I am aware it is not new to support the long centers or hot plates of ranges or similar cooking apparatus by a coil of water-pipes extending from the front to the rear of the furnace and communicating with the water-back proper and boiler of the range or stove. Furthermore, I am aware it is not new to support these long centers by means of water-chambers extending completely across from the front to the rear of ranges, &c., as such devices are seen in several patents; but I know of no instance where water-back linings have been provided with hollow lateral extensions capable of supporting the long centers of a stove or range, and my claims are limited to this construction of apparatus.

20 I claim as my invention—

1. A tubular lateral extension applied to the upper part of a water-back and supporting

the panels or long centers of a range or stove or other cooking or heating apparatus, substantially as described.

2. The communicating shells *E E' F*, of which the upper one, *E'*, is provided with a hollow lateral extension, *G*, as and for the purpose described.

3. A fire-box lined on each side with a water-back having a hollow extension that supports the panels or long centers of the cooking or heating apparatus containing said fire-box, substantially as described.

4. As a new article of manufacture, a tubular back or fire-box lining provided with a hollow lateral extension, for the purpose specified.

In testimony whereof I affix my signature in presence of two witnesses:

WM. MILLER.

Witnesses:

JAMES H. LAYMAN,
E. N. PARKER.
